UNITED STATES PATENT OFFICE

EINAR ARTHUR JOHNSON, OF BROOKLYN, NEW YORK

BULLET AND BULLET GUIDE

Application filed September 17, 1927. Serial No. 220,077.

This invention relates to improvements in bullets and bullet-guides, and the principles and ideas embodied herein are equally applicable to the projectiles emanating from guns 5 of small as well as large dimensions, or cannons.

It is well known, that it has been the object of experiments, so far in vain, to construct a bullet that would be subject to no retarding 10 influence on account of a vacuum, at the rear surface thereof, or rather a vacuumless bullet.

The one main obstacle in this respect consisted in the difficulty in discharging a bullet 15 without simultaneously twisting, or bending or demolishing the tapered rear-portion of same; upon its travel through the gun-barrel, it being clearly understood, that such a bullet, as a main feature in solving this problem, must have a rearwardly tapered or pointed 20 body.

With these considerations in view and for the purpose of overcoming the said obstructions, I have devised a medium, in the form 25 of a guide which may consist of any suitable material, such as, metal, compressed paper, fibre, wood, or the like substances, and which has for its object to encase the said bullet while in the shell and barrel of the gun, and protect and convey the said bullet 30 over the critical point, that is through the barrel of the gun when the shot is fired. The further procedure is as follows: The bullet with its encasement, or guide, the latter hereinafter termed the caboose, leave the gun 35 barrel together, but immediately the vacuum created by the flat or concave end of the caboose exerts a force sufficient to detach the caboose from the bullet thereby allowing the bullet to proceed unincumbered and without 40 a vacuum, upon its course; the caboose itself falling to the ground. In this manner by the use of a caboose all of the well known benefits and advantages of a vacuumless bullet are obtained without the loss of any of the pro- 45 pelling force of the full powder charge.

With the above and other objects in view, this invention consists of the novel features of construction, combination and arrangements of parts, hereinafter fully described, 50 claimed and illustrated in the accompanying

drawings forming parts of this specification, and in which similar characters of reference indicate corresponding parts in all views, and in which:

Figure 1 is substantially a longitudinal, 55 transverse, sectional view, illustrating an embodiment of the main features of my device applied to a bullet; Fig. 2 is a similar view of the said device, while Figs. 3 and 4 are detail views specifically referring to the 60 bullet itself.

Referring more particularly to the drawings 10 indicates a shell of the ordinary type; 11 designates the gunpowder, and 12 indicates the bullet with its tapered conical end-portion 13. Constructed to snugly fit the 65 said end-portion of the bullet is a caboose, or member 14, advancing at the front with its cylindrical sides to about the line 15, and having its rear portion constituting the inner 70 end of the projectile. The said member 14 is of the same diameter as the bullet and fit, as formerly said, into the shell constituting the rear end of the said projectile.

The frontal portion of the member 14 is 75 formed with a conical bore 16 terminating at the point 17; the depth and degree of tapering of the said member 14 corresponding exactly to the length and degree of tapering 80 of the conical rear end of the bullet, 13.

The said member 14 is provided with a 85 diametrical aperture 18 at the point of the apex 17 in order to facilitate the disengagement of the said member 14 from the bullet-portion 13 after the aforesaid members, as a compact unit, have left the gun-barrel.

A groove 19 is formed in the outer surface 90 of the member 14, and designed to contain greases, or oil, for the lubrication of the passage of the said member and bullet through the gun-barrel, as well as to collect carbon and other substances adhering to the interior of the gun-barrel.

The rear end 20 of the member 14 may 95 be either flat or provided with a concave surface; as indicated by dotted lines 21; while the distance between the said surface and the apex 17 of the cone may be varied according to the caliber of the bullet and its use.

In regard to the bullet itself, I propose to make that with the tapered rear portion hollow, which act may be accomplished either by constructing the said bullet, as shown in Fig. 3, where the hard steel shell is only filled up with a concrete matter to about the line 22, or where its tapered end-portion commences; or I may construct said end-portion separately, that is as a hollow shell, as indicated by 23 in Fig. 4, and thereupon connect the sections 23 and 24 together in any suitable manner, for instance, by welding.

It is evident that a construction of a bullet as just described will prove a notable advantage; thus such a bullet will as formerly stated eliminate a vacuum space, and as the rear portion is hollow and of no weight, it will not in any manner interfere with the course of the bullet, as the latter with the weight at its front will follow an unimpeded curve as destined.

From the foregoing it will be seen, that the said bullet with its vacuumless shape will be subject to the benefit of the full force of the powder charge, will be protected and conveyed safely on its travel through the gun-barrel, and will after leaving the latter embark upon its course free and unimpeded, gaining thereby potentialities of a magnitude that may prove revolutionary with respect to the science and technic governing this phase of industry.

It is obvious that changes may be made in the form, construction and arrangement of the several parts, as shown, within the scope of the appended claims, without departing from the spirit of the invention, and I do not therefore limit myself to the construction and arrangement shown and described herein.

What I claim as new, and desire to secure by Letters Patent of the United States, is:

1. A combination of a projectile with a bullet-guide, the former comprising a substantially cylindrical middle section, a forwardly slanting slightly curved front portion and a rear portion tapered to a fine point, the bullet-guide comprising a shell member provided at its front portion with a conical depression registering with the rear portion of the bullet, a transverse tubular perforation adapted to contact with the aforesaid fine point of the rear end of the bullet, an annular groove arranged upon the outer cylindrical surface of the said guide and near the end thereof and a concave depression formed upon the very end surface.

2. The combination of a projectile with a bullet-guide, the said projectile comprising a front and a rear section the front section having a substantially cylindrical body with a forwardly diminishing slightly curved end portion, and the rear section consisting of a conical shell-portion tapered rearwardly to a fine point, and means for connecting said front and rear sections rigidly together; the

said bullet-guide comprising a casing formed upon its frontal end surface with a central depression adapted to snugly fit the tapered rear portion of the said projectile, the said casing having a concrete rear end portion provided with a diametrically positioned tubular aperture intersecting the aforesaid fine point of the rearwardly tapered section of the projectile for the purpose of affecting disengagement during operation, an annular recess disposed upon the outer surface of the rear end of the said guide, and a slight concave depression formed upon the end surface of the latter.

Signed at New York city, in the county of New York and State of New York, this 1st day of September, A. D. 1927.

EINAR ARTHUR JOHNSON.
